MECHANICAL MOVEMENT

Peter G. Mangos, Minneapolis, Minn.

Application May 1, 1950, Serial No. 159,325

6 Claims. (Cl. 185—37)

1

My invention relates to improvements in mechanical movements.

The object of this invention is to provide a mechanical movement for use in imparting reverse rotary movement to a member in which the speed in one direction is greatly increased over that in the opposite direction.

To the above end, the invention consists of the novel devices and combination of devices hereinafter described and defined in the claims.

In the accompanying drawing, which illustrates the invention, like characters indicate like parts throughout the several views.

Referring to the drawing:

Fig. 1 is a view of the invention principally in central vertical section;

Fig. 2 is a sectional view taken centrally and vertically through the right-hand piston, shown in Fig. 1, on an enlarged scale;

Figs. 3 and 4 are elevational views of one of the cable guides and the port-equipped partition removed from the device, on the same scale as Fig. 2; and

Fig. 5 is a detail view principally in section taken substantially on the irregular line 5—5 of Fig. 4.

The numeral 6 indicates a housing having a semi-circular bottom member 7, a displaceable cover member 8, and leg brackets 9.

Within the housing 6 is a U-shaped cylinder 10, the transverse portion of which is semi-circular and comprises a plurality of segments 11. These segments 11, at their ends, and the side members 12 and 13 of the cylinder 10, at their lower ends, have outturned annular flanges 14. Adjacent pairs of flanges 14 are connected by a plurality of nut-equipped bolts 15. A screw cap 16 is applied to the upper end of each cylinder side member 12—13. The cylinder 10 is detachably secured to the housing 6 by upper and lower pairs of overlapping lugs 17 connected by nut-equipped bolts 18.

A pair of pistons 19—20 is mounted in the cylinder side members 12—13, respectively. At the longitudinal center of the cylinder segments 11 is a transverse partition 21. The cylinder 10 between the pistons 19—20 is filled with a fluid x which is poured into said cylinder through a filling opening 22 in the head of the piston 19. This filling opening 22 is normally closed by a screw plug 23, see Fig. 2.

The pistons 19—20 are connected by a cable 24 for common raising and lowering movements. The end portions of the cable 24 extend upwardly through the pistons 19—20 at their axes and are

2

arranged to be reversely wound on a shaft 25 journaled in bearings 26 on the side members of the housing 6 above the piston 19. The cable 24, between the pistons 19—20, extends through spiders 27 and over depending guides 28. These spiders 27 are in the form of flat disks interposed between the flanges 14 on the lower ends of the cylinder side members 12—13, and the upper ends of the uppermost cylinder segments 11 and secured thereto by the respective bolts 15.

The cable 24 is further guided, between the pistons 19—20, by a guide sheave 29 journaled on the partition 21 and a pair of guide sheaves 30 journaled on a pair of spiders 31 between the partition 21 and the spiders 27. The partition 21 and the spiders 31 are interposed between the remaining pairs of flanges 14 and are secured thereto by the respective bolts 15. Both pistons 19—20 are secured to the cable 24 in the same manner, but shown only in the piston 19. Secured to and within the lower end portion of the piston 19 is a spider 32. This spider 32 and the head of the piston 19 have aligned axial holes through which the cable 24 extends. A pair of clips 33 applied to the cable 24 within the piston 19 impinge sides of the head of the piston 19 and the spider 32 and connect said piston to the cable 24.

Formed in the partition 21 is a port 34 having a relatively large fluid-conducting capacity. This port 34 is normally closed by a valve 35 in the form of a disk, which closes on the side of the partition 21 toward the piston 19. The valve 35 is slidably mounted on three circumferentially spaced headed screws 36 which have threaded engagement with the partitions 21. A coiled spring 37 encircles each screw 36 and is compressed between the heads of said screws and the valve 35 and yieldingly holds said valve closed. Obviously, movement of the fluid x by downward movement of the piston 20 will open the valve 35. An open port 34' in the partition has a relatively small fluid-conducting capacity.

An upper bar 38 and a lower bar 39 extend between the cylinder side members 12 and 13 and are rigidly secured thereto. A pair of posts 40 extend between the bars 38—39 and are rigidly secured thereto. A spring base 41 in the form of a horizontal bar has in its end portions holes through which the posts 40 loosely extend. A coiled spring 42 encircles each post 40, is compressed between the upper bar 38 and the spring base 41 and yieldingly holds said spring base 41 on the lower bar 39. The spring base 41 is attached to the shaft 25 by a cable 43 and ar-

ranged to be wound thereon to lift said spring base.

One end of the shaft 25 extends outwardly of the housing 6 and is equipped with a large wide pulley 44. A cable 45 has one of its ends secured to the pulley 44 to be wound thereon. An elevator platform 46 is attached to the other or lower end of the cable 45.

Normally, the pistons 19-20 are as shown and the spring 42 yieldingly holds the shaft rotated into a position in which the cable 43 is wound on the pulley 44 and holds the elevator platform 46 raised. The raising and lowering of the elevator platform 46 is controlled by the ports 34-34' and the valve 35.

When a load of sufficient weight to overcome the spring 42 is placed on the elevator platform 46, when raised, said platform will move downwardly, unwind the cable 45 therefrom and rotate the pulley 44 and the shaft 25. Rotation of the shaft 25 will wind the end portion of the cable 24 leading from the piston 29 and lift said piston. Upward movement of the piston 20 will pull the piston 19 down by means of the cable connection 24. Downward movement of the piston will force the fluid α through the port 34' and thus cause the elevator platform 46 to move slowly until the piston 19 has reached its lowermost position and the piston 20 is in its uppermost position. During the downward movement of the elevator platform 46, the rotation of the shaft 25 will wind the cable 43 thereon, raise the spring base 41 and compress the springs 42 and place the same under tension.

When the load is removed from the elevator platform 46, the tensioned springs will force the spring base 41 downwardly and the pull on the attached cable 43 will unwind said cable and thereby rotate the shaft 25 in a direction to wind the end portion of the cable 24 leading from the piston 19 and lift said piston. This lifting of the piston 19 will pull the piston 20 down and thereby force the fluid α to open the valve 35 and flow through the two ports 34 and 34' and thus cause the elevator platform 46 to move upwardly very fast in comparison with the downward movement thereof.

What I claim is:

1. In a device of the class described, a cylinder, a pair of pistons in the cylinder, a transverse partition in the cylinder between the pistons, a fluid in the cylinder between the pistons, a port in the partition having a relatively large fluid-conducting capacity, a valve normally closing the port, said valve being constructed and arranged to be opened by pressure of the fluid produced by the lower one of the pistons and held closed by pressure of the fluid produced by the lowering of the other piston, an open port in the partition having a relatively small fluid-conducting capacity, and means for alternately and successively raising and lowering the pistons in which they move relatively fast, when the valve is open and the fluid is being forced through the two ports by the piston on the opening side of the valve, and move relatively slow when the valve is closed and the fluid is being forced through the open port, by the piston on the closing side of the valve, said cylinder being U-shaped, the transverse member thereof being semi-circular, and the pistons being one in each of the side members of the cylinder.

2. The structure defined in claim 1 further including a cable in the cylinder extending through the partition and connecting the pis-

tons, and means in the cylinder for guiding the cable.

3. The structure defined in claim 1 in which the cylinder is U-shaped, the transverse member thereof is semi-circular and the pistons are one in each side member of the cylinder, said structure further including a cable in the cylinder extending through the partition and connecting the pistons, and radial spiders in the semi-circular portion of the cylinder and having guides for the cable.

4. In a device of the class described, a U-shaped cylinder having a central transverse partition, a pair of pistons in the cylinder, one on each side of the partition, one of the pistons being raised and the other lowered, a shaft overlying the cylinder, a cable extending through the cylinder and connecting the pistons for common movement, the end portions of the cable being attached to the shaft and arranged to be reversely and alternately wound and unwound thereon, a fluid in the cylinder between the pistons, a port in the partition having a relatively large fluid-conducting capacity, a yieldingly closed valve normally closing the port, said valve being constructed and arranged to be opened by pressure of the fluid produced by the lowering of one of the pistons and held closed by pressure of the fluid produced by the lowering of the other piston, an open port in the partition having a relatively small fluid-conducting capacity, spring means normally holding the shaft with the piston on the closing side of the valve raised and the other piston lowered, a sheave on the shaft, and a load-carrying cable arranged to be wound on the sheave by rotation thereof by the spring means to lower the piston on the opening side of the valve and the raising of the other piston, when a load of sufficient weight is attached to and held suspended by the load-carrying cable to overcome the tension of the spring means it will be lowered by the unwinding of the load-carrying means, the lowering of the weight rotating the shaft to lower the raised pinion and raise the lowered pinion and place the spring means under tension.

5. The structure defined in claim 4, further including means for guiding the first-noted cable between the pistons.

6. The structure defined in claim 4 in which the transverse portion of the cylinder is semi-circular, and further including radial spiders in the cylinder having means for guiding the first-noted cable between the pistons.
